DUAL COIL-ELECTRIC RELAY

Edward J. Rabenda, Poughkeepsie, N. Y., assignor
to International Business Machines Corpora-
tion, New York, N. Y., a corporation of New
York

Application March 3, 1948, Serial No. 12,851

1 Claim. (CL 175—337)

1

This invention relates to electromagnetic re-
lays of the type used in electrical accounting
machines wherein a plurality of such devices
may be electrically connected in parallel.

It is common practice in record controlled
electrical accounting machines to operate a plu-
rality of relays and other electromagnetic de-
vices some of which may be connected together
electrically, in parallel, at one time or another
due to the timed sequence operation of such
machines. It is also common to have multicoil
relays in such circuits wherein one coil of a
relay is energized to pick up or attract an ar-
mature and another coil on the relay is used to
hold or retain the armature attracted. Such
arrangements are essential to the peculiar mode
of operation requirements with such machines.

Normally the so-called dual coil relays are
constructed having two coils wound upon the
same core, in some relays with one coil wound
over the other and in others with the windings
abutting each other. Usually the impedance
and ampere-turn ratios of these windings are
arranged so that one coil, known as the pick-up
coil, when energized, attracts the armature in
a very short period of time, while the coil, known
as the holding coil, when energized, retains the
armature attracted. These characteristics are
required in their use with electrical accounting
machines due to the circuit complexity and
rapidity of operation of such mechanisms. For
the same reason the pick-up and holding coils
of a specific relay frequently are connected in
parallel with similar coils in other relays, or
with dissimilar coils, or with other closed cir-
cuits.

It has been found that where dual coil relays
are connected to have one or the other of their
windings in parallel in the manner described
above, certain deleterious effects may result.
For example, where a holding coil is connected
in parallel with another holding coil the pick-up
coil has been found to function sluggishly in
attracting its relay's armature. Conversely,
where a pick-up coil is connected in parallel with
another pick-up coil, it has been found that
when the holding coil of the relay releases the
armature time has been required. In the last
mentioned situation there is also a tendency
for the second mentioned relay pick-up coil to
be energized by the de-energizing of the holding
coil of the first mentioned relay. The phe-
nomena just observed are traceable to the trans-
former action inherent in dual coil relays and
to the circulating currents set up therein under

2

certain circuit conditions arising in the operation
of very high speed electrical accounting ma-
chines.

The primary object of this invention is to pro-
vide an improved dual coil relay device wherein
the mutual inductive relationship between the
coils is reduced to a minimum.

A further object of this invention is to provide
a dual winding electromagnet wherein the mu-
tual reluctance of the common magnetic paths
is increased to a maximum.

Other objects of the invention will be pointed
out in the following description and claim and
illustrated in the accompanying drawings, which
disclose, by way of example, the principle of
the invention and the best mode, which has been
contemplated, of applying that principle.

In the drawing:

Fig. 1 is a front elevation view of the inven-
tion.

Fig. 2 is a diagrammatic view of the magnetic
flux distribution in a conventional type dual coil
relay.

Fig. 3 is a diagrammatic view of the magnetic
flux distribution in a dual coil relay of the type
disclosed in the present invention when the relay
armature is first attracted by the pick-up coil
being energized.

Fig. 4 shows the magnetic flux distribution in
a relay of the type herein disclosed when both
the pick-up and holding coils are energized.

Fig. 5 illustrates the magnetic flux distribution
in a further modification of the present inven-
tion as applied to a dual coil relay having its
armature closed and both the pick-up and hold-
ing coils being energized.

Referring now to Fig. 1, a coil 10 and a coil
11 are mounted respectively upon the legs 12
and 13 of a relay magnetic core 14 having a
third leg 15 at one end of which is pivotally
fastened an armature 16. The armature 16 is
connected by a link 17 to a movable contact
member 18. With the arrangement of the coils
10 and 11 as shown the interlinkages of mag-
netic flux via the core and via stray flux paths
are reduced; this feature, however, is best illus-
trated by reference to Figs. 3, 4, and 5.

Fig. 2 illustrates the flux distribution in a
conventional relay having a pick-up coil P, a
holding coil H, a core C, and an armature A
pivoted on the core C by a pivot Q. In this
type of dual coil relay the magnetic flux set up
by energization of either the pick-up coil (dash
dot lines) or the holding coil (dash lines) passes
through the magnetic path of the other coil.

including even a part of the stray flux paths of each coil. It is obvious that transformer action occurs in relays of this type in the manner previously described.

Fig. 3 shows the flux distribution in a dual coil relay according to the present invention, wherein a magnetic core C has a leg M about which is wound a holding coil H, a leg L about which is wound a pick-up coil P, and a leg K to one end of which an armature A is pivoted by a pivot Q, the armature A being in its normally open position. Flux set up by the pick-up coil P (dash dot lines), except for stray flux, is principally confined to the leg L, part of the core C, the leg K, and the armature A, little or none of this flux being interlinked with the holding coil H. Conversely flux set up by the holding coil H is principally confined to stray flux and the return path of leg M, little or none of the flux being interlinked with the pick-up coil P due to the high reluctance of the air gaps between leg M, leg L, and armature A. When, however, the armature is closed, as shown in Fig. 4, interlinkage of the magnetic flux of coil P with coil H does occur, and vice versa. In this instance, however, an alternate flux path is provided in either event by the leg K so that the flux passing through either coil as a result of the other's being energized is proportionately reduced. Consequently the transformer action in the mode of the present invention illustrated in Figs. 3 and 4 is reduced considerably over that occurring in a conventional type relay such as illustrated in Fig. 2.

It has been found that a considerable influence is exerted mutually between the holding and pick-up coils by the stray flux. For purposes of clarity the diagrams of Figs. 2, 3, and 4 have not been drawn to show the stray flux influence. The arrangement of the coils 10 and 11, however, as shown in Fig. 1, is such that the pick-up coil 10 is placed at one end of the leg 12 while the holding coil 11 is placed at the opposite end of the leg 13. This separation of the pick-up and holding coils in an arrangement as in the present invention has the effect of further reducing the mutual flux path and hence the transformer action between the coils.

Fig. 5 illustrates a further modification of the subject invention wherein a core C has a leg M about which is wound a holding coil H, a partial leg L about which is wound a pick-up coil P, and a leg K to one end of which is pivoted an armature A by a pivot Q, the partial leg L being attached to the core C by a non-magnetic portion B. The non-magnetic portion may be inserted in a relay of the type shown in Fig. 1 as a portion of the leg 12 lying between the reference lines

a—b. With the arrangement of Fig. 5, practically no mutual flux path between the coils H and P exists, and similarly little, if any, transformer action is obtained since the flux as a result of coil P (dash dot lines) consists principally of the stray flux and return path of the armature A and the leg L while the flux resulting from the coil H (dash line) is largely confined to stray flux (separated physically from influencing coil P) and the path composed of leg M, core C, leg K, and armature A. The flux from the coil H is further isolated from influencing coil P when the armature A is in its normally open position as in Fig. 4.

While there have been shown and described and pointed out the fundamental novel features of the invention as applied to a preferred embodiment, it will be understood that various omissions and substitutions and changes in the form and details of the device illustrated and in its operation may be made by those skilled in the art without departing from the spirit of the invention. It is the intention, therefore, to be limited only as indicated by the scope of the following claim.

What is claimed is:

25 15 An electromagnet having a U-shaped core of a predetermined cross-section and a second core of a substantially greater cross-section central thereof and parallel with the arms of the first said core, the ends of all said cores forming the 30 pole faces of the said magnet, an armature extending over the said pole faces, a lumped winding on one of the said arms and located at the bottom of the said U-shaped member, and a second lumped winding on the said second core located at the pole face thereof, whereby the stray flux effect of the first said winding relative to the said armature is reduced to a minimum and the stray flux effect of the second said winding is increased to a maximum.
